UNITED STATES PATENT OFFICE.

JOHN J. BUERO, OF CHARLESTON, SOUTH CAROLINA.

CUT-OUT AND SWITCH.

1,168,247.

Specification of Letters Patent. Patented Jan. 11, 1916.

Application filed April 21, 1914. Serial No. 833,336.

To all whom it may concern:

Be it known that I, JOHN J. BUERO, a citizen of the United States, and a resident of Charleston, in the county of Charleston and State of South Carolina, have made certain new and useful Improvements in Cut-Outs and Switches, of which the following is a specification.

My invention is an improvement in cut out switches, and has for its object to provide a switch of the character specified, especially adapted for use between high tension conductors and buildings, wherein mechanism is provided in connection with the switch for preventing over charging of the wiring of the building in case of breakdowns or improper action of the transformers, the said mechanism being so arranged that an increase of voltage above a predetermined point will operate the said mechanism to disconnect the wiring of the building and to shunt the current to ground.

In the drawings:—Figure 1 is a front view of the improved switch, Figs. 2 and 4 are sections on the lines 2—2, and 4—4, respectively, of Fig. 1, looking in the direction of the arrows adjacent to the line, and Fig. 3 is a rear view.

The present embodiment of the invention comprises a base 1 of insulating material, as for instance glass, porcelain, hard rubber or the like, the base being adapted for attachment to a fixed support at a suitable point, and the base is provided with the usual openings 3 for receiving screws or the like to hold the same to the support. Binding posts 2 and 2^a are arranged at one end of the base, for engagement by lead wires connected with the supply wires for the current. Other binding posts 4 and 4^a are arranged at the opposite ends of the base, the said posts being spaced apart laterally from each other, and registering with the posts 2 and 2^a at the other end, and the posts 4 and 4^a are adapted for connection with the service wires of the house circuit or system.

Fuse plugs 7 and 7^a of usual construction are mounted on the base, adjacent to the posts 2 and 2^a, and each fuse plug is connected to the adjacent binding post 2 or 2^a by means of conducting strips 8 and 8^a, the said strips being secured at one end to the binding post and being connected at the other to the adjacent fuse plug.

A double pole single throw switch is provided for connecting the binding posts 4

and 4^a with the spring contact plates which in turn are connected with the fuse plugs. The switch consists of the usual cross bar 9 of insulating material, as for instance hard rubber or the like, and provided intermediate its ends with the handle 10 for convenience in operating the switch, and the handle is connected with the arms 11 and 11^a of the switch. Each arm 11 and 11^a is connected to the adjacent binding post 4 or 4^a, by means of the connections 12 and 12^a on the switch board, the said connections being connected to the binding posts by conducting strips 13 and 13^a.

Each switch arm is pivoted between the strips or contact plates of the connection 12 or 12^a, and each of the said arms is adapted to move between a pair of spring contact plates 14 or 14^a at the end adjacent to the fuse plugs, to connect the binding post 4 or 4^a to the fuse plug. Each pair of contact plates 14 and 14^a is connected to the adjacent fuse plug by a conducting strip 15 or 15^a as the case may be, the said strips being arranged on the under side of the base, as shown in Fig. 3, and preferably the strips 15 and 15^a are arranged in recesses, which may be filled with an insulating plastic compound capable of hardening.

The attachment comprises a strip 16 of conducting material, which is connected at one end to the pair of contact plates 14, by means of a screw bolt 17. The bolt is passed through the base, and through the base plate 90 which supports the contact plates 14, and through the strip 16, and is then engaged by a nut 18 to bind the parts together. The strip 16 has its intermediate portion offset upwardly from the face of the base, as shown more particularly in Fig. 4, and a second strip 19 is arranged longitudinally of the base between the switch arms, and the strip 19 is connected at one end to the strip 16 at approximately the center thereof. The connection may be made by means of a rivet, as shown at 20, and the opposite end of the strip 19 is connected to a binding post 21, which is connected with suitable ground, by means of a lead wire 22.

The ground wire should be connected to the ground in the usual manner. Intermediate the ends of the strip 19 a screw bolt 23 is passed upwardly through the base, and the said bolt passes through an opening in the strip 19, and is engaged by a thumb nut 24 above the strip. That end of the strip

19 adjacent to the strip 16 is offset upwardly, as shown more particularly in Fig. 2, and the free end of the strip 16 would normally contact with the base plate of the 5 contact plates 14^a, if there were nothing between the said free end of the strip and the contact plate. A plate or block 25 of mica or other suitable material is, however, arranged between the said free end of the 10 strip and the base plate, the plate or block acting normally to hold the free end of the strip out of contact with the base plate.

Under ordinary conditions, without the attachment, constituted by the strips 16 and 15 19 and connected parts, should there be a break down in the transformer, there would be the house wiring carrying 2,000 volts from the supply wires, and if there were no trouble or defect in the wiring of the building 20 this high voltage would be ready for the first person who should touch the wiring, and would probably kill such person immediately. Were there bad wiring or defects on the house circuit, the current would 25 possibly set fire to the house. With the attachment, however, the high voltage would perforate the mica plate or the block 25, and the current would pass by way of the strip 16 and the strip 19 to the binding post 21, and by way of the ground wire 22 thus 30 protecting the house wiring. Were the binding post 21 not connected to the ground, the high voltage would cause the current to perforate the mica plate, and the fuse plugs 35 would blow out in the usual manner.

The device acts with or without the ground wire, the ground wire, however, furnishing an additional protection.

The improved switch is grounded at one 40 side of the circuit, thus combining a lightning arrester with a permanent ground on one side of the circuit. This arrangement complies with the rules of the National Board of Fire Underwriters.

45 I claim:—

1. In combination with a cut out switch, comprising an insulating base, and pairs of binding posts at the opposite ends of the base for connection with the supply wires, 50 and the service wires respectively, a double pole single throw switch connected with the binding posts for the service wires, pairs of spring contact plates for engagement by the switch, said contact plates being connected with the adjacent binding posts of the first-named pair, and the switch being 55 provided for connecting the last-named

binding posts with the contact plates, a fuse plug arranged between each of the first-named binding posts and the adjacent pair 60 of contact plates for the switch, and a protecting device for shunting an excess of current above a predetermined voltage from one pair of contact plates to the other or to the ground, and adapted to be brought 65 into operation by the excess in voltage, said device comprising a conducting strip detachably connected with one pair of contact plates, and normally adapted to contact at the other end with the other pair, a plate 70 of mica arranged between the strip and the said last named pair, and means for tensioning the pressure of the strip, said means comprising a second contact strip arranged longitudinally of the base and connected at 75 one end to the first-named strip intermediate its ends, a binding post on the base for connection with a ground wire to which the other end of the last named strip is connected, and a set screw in connection with 80 the base and engaging the last-named strip to vary the tension thereof.

2. In combination with a cut out switch, comprising an insulating base, and pairs of binding posts at the opposite ends of the 85 base for connection with the supply wires, and the service wires respectively, a double pole single throw switch connected with the binding posts for the service wires, pairs of spring contact plates for engagement by the 90 switch, said contact plates being connected with the adjacent binding posts of the first-named pair, and the switch being provided for connecting the last-named binding posts with the contact plates, a fuse plug arranged 95 between each of the first-named binding posts and the adjacent pair of contact plates for the switch, and a protecting device for shunting an excess of current above a predetermined voltage from one pair of contact 100 plates to the other or to the ground, and adapted to be brought into operation by the excess in voltage, said device comprising a conducting strip detachably connected with one pair of contact plates, and normally 105 adapted to contact at the other end with the other pair, a plate of mica arranged between the strip and the said last named pair, and means for tensioning the pressure of the strip.

JOHN J. BUERO.
